BREAKER STRIP CONSTRUCTION

Ralph E. Wallenbrock and John J. Voda, Evansville, Ind., assignors to International Harvester Company, a corporation of New Jersey

Application February 28, 1950, Serial No. 146,659

5 Claims. (Cl. 220—9)

1

This invention relates to refrigerator cabinet construction and more particularly to a breaker strip assembly for a refrigerator cabinet.

The primary object of this invention is to provide a novel breaker strip construction in which a breaker strip of molded plastic or rubber is used to bridge the space between the inner and outer walls of a refrigerator cabinet.

Another object is to provide a breaker strip formed with projections along each edge thereof which are secured in place by clip members, thus providing a means of securing the breaker strip in place by use of a very minimum of parts.

Still another object is to provide a breaker strip that can be easily and quickly installed or removed from a refrigerator cabinet.

A further object is to form a breaker strip with transverse ribs on one side which will act as strengthening members, thus providing a breaker strip which is relatively thin but of sufficient strength for normal usage.

A still further object is to provide a simplified means of sealing around a breaker strip to prevent any entrance of air or moisture between the inner and outer walls of a refrigerator cabinet.

These and other objects and advantages of the invention will be apparent from consideration of the following description and claims taken in accordance with the accompanying drawings, in which:

Fig. 1 is a top view of a refrigerator cabinet or chest having the food storage compartment door in open position.

Fig. 2 is an enlarged sectional view taken on the line 2—2 of Fig. 1.

Fig. 3 is a perspective of the under side of a portion of the breaker strip shown in Fig. 2.

Fig. 4 is a sectional view of a modified structure.

Fig. 5 is a perspective of the under side of a portion of the breaker strip shown in Fig. 4.

Although the construction illustrated could be used in a refrigerator cabinet having a front opening, it is illustrated in a cabinet or chest 10 having a top opening door 11 hingedly connected to the cabinet wall. The illustrated cabinet wall has an outer wall 12, an inwardly spaced inner wall 13 and insulating material 14 disposed between said walls.

As illustrated in Figs. 2 and 3, the outer wall 12 is provided with a downwardly and inwardly bent portion which forms a rounded edge 15 and a channel 16 having a leg 17 adjacent the outer wall, a bottom portion 18 perpendicular to the outer wall and a second leg 19 parallel to said

2

first leg and having an edge 20 located in the same horizontal plane as edge 15.

The inner wall 13 is provided with a downwardly and outwardly bent portion which forms a rounded edge 21 lying in the same horizontal plane as edge 15 and a channel 22 having a leg 23 adjacent the inner wall, a bottom portion 24 bent perpendicular to the inner wall, and a second leg 25 bent parallel to the first leg and having an edge 26 located in the same horizontal plane as edge 21. The channels 16 and 22 form upwardly opening grooves or pockets 27 and 37 respectively around the door opening.

A breaker strip 28 of a one-piece "picture frame" construction bridges the space between said inner and outer wall with lip 29 overlapping edge 15 and lip 30 overlapping edge 21. The breaker strip is of molded plastic or rubber and has spaced transverse ribs 31 formed along its bottom side. These ribs act as strengthening members and eliminate the necessity of positioning separate supporting members under said breaker strip. Cylindrical projections 32 and 38 are also formed on the bottom side of said breaker strip and are spaced apart along the length of the breaker strip. There is a row of projections spaced inwardly from lip 29 and a second row spaced inwardly from lip 30.

The bottom portions 18 and 24 of said channels are provided with holes 33 which are spaced apart in alignment with projections 32 and 38. Into these holes are positioned tubular clip members 34 having ears 35 which secure the clips to said channels. The projections are of sufficient length to extend down through the clips. The inside diameter of the clips tapers to a smaller diameter toward the bottom of said clip so as to provide a press-fit between the projections and clips, thus securing the projections in place. By this arrangement the breaker strip is secured in place with the lips 29 and 30 in close contact with edges 15 and 21 respectively and portions of said breaker strip in contact with channel edges 20 and 26.

45 A gum-like sealing material 36 having a resinous or asphalt base is disposed in channel grooves 27 and 37 which fills the grooves completely and sticks to the breaker strip adjacent to edges 15, 20, 21 and 26 so as to completely seal around said breaker strip. This prevents the entrance of any air or moisture into the insulation space between the inner and outer walls.

In assembling the breaker strip, the clips 34 are first pushed down through holes 33 until ears 35 have passed through said holes and have

sprung out and secured the clips to the channels. The gum-like sealing material is then placed in the channel grooves 27 and 37 of sufficient quantity to completely fill the grooves. The one-piece breaker strip is then positioned with the projections 32 and 38 in alignment with clips 34 and then forced down so that the projections will cut through the sealing material and be pressed-fitted into the inside diameter of the clips. By this arrangement a breaker strip is provided which can be quickly installed, requires only a few parts and completely seals the insulating space between the inner and outer walls of a refrigerator cabinet.

In the modified structure as shown in Figs. 4 and 5, a breaker strip 45 bridges the space between walls 12 and 13 and is formed with lips 46 and 47 which overlap edges 15 and 21. Longitudinal ribs 39 and 40 are formed on the under side of said breaker strip spaced inwardly from lips 46 and 47 respectively. Along the bottom edge of rib 30 cylindrical projections 42 are formed. The projections 41 and 42 are spaced apart along the length of said breaker strip and are held in place by the clips 34 as described above. Transverse ribs 43 are formed on the under side of the breaker strip and serve as strengthening members. The ribs 39 and 40 are embedded in the sealing material 36, thus preventing the entrance of any moisture or air into the space between walls 12 and 13. In this arrangement only a small amount of sealing material is required since a complete seal will be formed as long as the lower portion of ribs 39 and 40 are embedded in the sealing material.

It will, of course, be understood that various changes in details of construction and arrangement of parts may be made by those skilled in the art without departing from the spirit of the invention as set forth in the appended claims.

What is claimed is:

1. In a refrigerator cabinet construction having spaced apart walls, a channel adjacent the terminal edge of each of said walls having a pair of legs connected by a web portion having holes therein, the terminal free end of each of said pair of said legs being in alignment with the terminal edge of its respective wall, clip members secured in said holes, a breaker strip connecting said walls, said breaker strip having its edges formed to provide a pair of lips, each of said lips being positionable to overlap a respective wall, said breaker strip further having a flat portion adjacent each lip on one side thereof, each of said flat portions being adapted to bridge a respective channel and abut the terminal free ends of the legs thereof, said flat portions having projections depending therefrom adapted to extend into said channels and be secured in place by said clip members, and a sealing material contained in said channels cooperable with said breaker strip and walls for hermetically sealing the space between the walls.

2. In a refrigerator cabinet, the combination of: spaced apart walls having insulating material disposed therebetween and being formed to define a door opening, said walls terminating in spaced apart edge portions peripherally of the door opening, said edge portions being bent inwardly toward each other to form a channel along each wall, each of said channels having a pair of legs connected by a web portion having holes therein, the terminal free ends of said legs of each channel being in alignment with each other, tubular clip members secured in said holes,

and a breaker strip connecting said walls, said breaker strip having its edges formed to provide a pair of lips, each of said lips being positionable to overlap a respective wall, said breaker strip further having a flat portion adjacent each lip on one side thereof, each of said flat portions being adapted to bridge a respective channel and abut the terminal free ends of the legs thereof, said flat portions having cylindrical projections depending therefrom adapted to extend into said channels and be engaged by said clip members, said breaker strip being molded with transverse ribs extending between the flat portions.

3. The combination as set forth in claim 2, in which sealing means cooperable with said walls and said breaker strip are provided for hermetically sealing the space between said walls, said means including a sealing material contained within said channels.

4. In a refrigerator cabinet, the combination of: spaced apart walls having insulating material disposed therebetween and being formed to define a door opening, said walls terminating in spaced apart edge portions peripherally of the door opening, said edge portions being bent inwardly toward each other to form a channel along each wall, each of said channels having a pair of legs connected by a web portion having apertures therein, the terminal free ends of said legs of each channel being in a common plane and in alignment with each other, tubular clip members secured in said apertures, a breaker strip connecting said walls, said breaker strip having its edges formed to provide a pair of lips, each of said lips being positionable to overlap a respective wall, said breaker strip further having a flat portion adjacent each lip on one side thereof, each of said flat portions being adapted to bridge a respective channel and abut the terminal free ends of the legs thereof, said flat portions having cylindrical projections depending therefrom adapted to extend into said channels and be press-fitted into engagement with said clip members, said breaker strip being molded with transverse ribs extending between the flat portions for strengthening the breaker strip, and sealing means cooperable with said walls and breaker strip for hermetically sealing the space between said walls, said means including sealing material contained within and substantially filling said channels and contacting said flat portions.

5. In a refrigerator cabinet, the combination of: spaced apart walls having insulating material disposed therebetween and being formed to define a door opening, said walls terminating in spaced apart edge portions peripherally of the door opening, said edge portions being bent inwardly toward each other to form a channel along each wall, each of said channels having a pair of legs connected by a web portion having holes therein, the terminal free ends of said legs of each channel being in a common plane and in alignment with each other, clip members secured in said holes formed in said web portions, a breaker strip connecting said walls, said breaker strip having its edges formed to provide a pair of lips, each of said lips being positionable to overlap a respective wall, said breaker strip further having a flat portion adjacent each lip on one side thereof, each of said flat portions being adapted to bridge a respective channel and abut the terminal free ends of the legs thereof, each of said flat portions having a rib depending therefrom adapted to be disposed between the

legs of a respective channel, said ribs having projections extending therefrom adapted to be secured to said clip members, and sealing means cooperable with said walls and said ribs for hermetically sealing the space between said walls, 5 said means including sealing material contained within and partially filling said channels, a portion of said ribs being imbedded in said sealing material.
